DESIGN FOR A GEOGRAPHICAL GLOBE

Joseph V. Clark, Ann Arbor, Mich.

Application May 12, 1939, Serial No. 84,949

Term of patent 14 years

To all whom it may concern:

Be it known that I, Joseph V. Clark, a citizen of the United States, residing at Ann Arbor, in the county of Washtenaw and State of Michigan, have invented a new, original, and ornamental Design for a Geographical Globe, of which the following is a specification, reference being had to the accompanying drawing, forming a part thereof.

Figure 1 is a perspective of one side of a geographical globe showing my design, and

Figure 2 is a perspective showing the opposite side of said geographical globe.

I claim:

The ornamental design for a geographical globe, as shown.

JOSEPH V. CLARK.
